1042,605

UNITED STATES PATENT OFFICE.

ARTHUR ROSENHEIM, OF BERLIN, GERMANY.

MANUFACTURE OF HYPOPHOSPHORIC ACID AND OF ITS SALTS.

1,042,605.

Specification of Letters Patent.

Patented Oct. 29, 1912.

No Drawing.

Application filed June 21, 1911. Serial No. 634,408.

To all whom it may concern:

Be it known that I, ARTHUR ROSENHEIM, a citizen of the German Empire, residing at Berlin, Germany, have invented certain new and useful Improvements in the Manufacture of Hypophosphoric Acid and of its Salts, of which the following is a specification.

This invention relates to the manufacture of hypophosphoric acid and of its salts and consists in electrolytically oxidizing anodes consisting of phosphids. Suitable phosphids are for instance phosphids of copper, silver, nickel and tin. The electrolysis is preferably effected with a weak acid electrolytical bath and with a cathode consisting of the metal contained in the phosphid. If the voltage is kept in suitable limits preferably from 3 to 10 volts a good yield of hypophosphoric acid up to 60% of the phosphorus entering into solution is obtained in addition to phosphoric acid. If the voltage is permanently kept higher the percentage of phosphoric acid is increased if on the contrary the voltage is kept lower the quantity of phosphorus and hypophosphorous acid increases.

Care is to be taken that in acidulating the bath solution strongly oxidizing acids such as nitric acid or acids which develop oxidizing products during electrolysis such as halogenous hydrogen acids and acids of low conductive property are avoided. Sulfuric acid as a solution of 1 to 10% and formic acid of the same concentration are most available. Small quantities of comparatively weak oxidizing agents such as chromic acid may be added to the electrolyte as catalytic substances.

The electrolysis can be effected with or without diaphragm for separating the anode space from the cathode space.

The electrolysis is kept in operation till the most part of the metal phosphid used as anode is dissolved. Then the electrolyte is drawn off or separated from the metal sponge by filtering. The electrolyte may then be used directly as a solution of hypophosphoric acid or half of its volume may be neutralized by carbonate of soda and after

addition to the second half of the electrolyte the liquid may be concentrated so that the difficultly soluble acid sodium hypophosphate $\text{NaHPO}_3 \cdot 2\text{H}_2\text{O}$, is crystallized out from the solution.

55

What I claim is:—

1. Process of manufacturing hypophosphoric acids and its salts comprising electrolytically oxidizing metalphosphid anodes.

2. Process of manufacturing hypophosphoric acids and its salts comprising electrolytically oxidizing metalphosphid anodes in opposition to cathodes containing the metal of the phosphid anodes.

3. Process of manufacturing hypophosphoric acids and its salts comprising electrolytically oxidizing metalphosphid anodes in a weakly acid electrolyte at a voltage from 3 to 10 volts.

4. Process of manufacturing hypophosphoric acids and its salts comprising electrolytically oxidizing metalphosphid anodes in a weakly acid electrolyte at a voltage from 3 to 10 volts in opposition to cathodes containing the metal of the phosphid anodes.

5. Process of manufacturing hypophosphoric acids and its salts comprising electrolytically oxidizing metalphosphid anodes in a well conducting weakly acid electrolyte substantially free from acids with strongly oxidizing effects.

6. Process of manufacturing hypophosphoric acids and its salts comprising electrolytically oxidizing metalphosphid anodes in a well conducting weakly acid electrolyte substantially free from acids with strongly oxidizing effects in opposition to cathodes containing the metal of the phosphid anodes.

7. Process of manufacturing hypophosphoric acids and its salts comprising electrolytically oxidizing metalphosphid anodes in a weakly acid electrolyte containing small quantities of weakly oxidizing substances.

In testimony whereof, I affix my signature in presence of two witnesses.

ARTHUR ROSENHEIM.

Witnesses:

HENRY HASPER,
WOLDEMAR HAUPT.
